UNITED STATES PATENT OFFICE.

ELLSWORTH E. FLORA AND JOHN F. MURPHY, OF CHICAGO, ILLINOIS, ASSIGNEES TO
THE SEAL & FASTENER CO., OF CHICAGO, ILLINOIS, A CORPORATION OF DELAWARE.

TOOL FOR JOINING METAL-STRAP ENDS.

1,083,607.

Specification of Letters Patent.

Patented Jan. 6, 1914.

Application filed September 2, 1913. Serial No. 787,711.

To all whom it may concern:

Be it known that we, ELLSWORTH E. FLORA and JOHN F. MURPHY, citizens of the United States, residing at Chicago, in the county of Cook and State of Illinois, have invented a new and useful Improvement in Tools for Joining Metal-Strap Ends, of which the following is a specification.

The present invention relates to an improved construction of tool for joining mutually-overlapping straps by crimping them edgewise into infolding contact, thereby locking the parts against relative movement.

15 The method of forming the joint thus referred to is the subject of Letters Patent of the United States No. 1,038,108, granted September 10, 1912; and the present tool is an improvement on that set forth in Letters Patent of the United States No. 1,038,109, granted on the same date.

20 The primary purpose of the present improvement is to provide a massive construction of the aforesaid tool, adapted to perform its work in stationary position on heavy metal straps, such as are used on cotton-bales and as hoops on barrels, and the like.

25 In the accompanying drawings, Figure 1 is a plan view of the tool, with the operating handle broken away; Fig. 2 is a section on line 2—2, Fig. 1; Figs. 3 and 4 are sections respectively on line 3 and line 4, Fig. 1; Fig. 5 is a perspective view of one of the crimping-pin blocks; Fig. 6 is a section on line 6, Fig. 1, showing the jaws in their separated relation with the work to be operated upon supported in place between them; Fig. 7 is a view similar to Fig. 6, but showing the jaws closed upon the work, and Figs. 8 and 9 are, respectively, a back view and an edge-view showing strap-ends joined together by the interlocking crimps formed by the tool.

40 The bed-frame is a hollow casting formed with a back-wall 10, a front wall 11 and side-walls 12, all rising from a base 13, which is bolted through its lateral extensions beyond the side-walls to a support or floor 14. From the front wall extends a flat bed 15 terminating at its forward end in an anvil 16 to serve, in convenient position, for hammering out thereon bends or kinks in straps to be joined, and for general anvil purposes.

45 In a rectangular recess 17 provided in the forward raised end of the bed fits and is rigidly bolted in place a jaw 18 formed with a lip 19. This stationary jaw has formed in it, at each side of its transverse center, a rectangular recess, in which fits a block 20 (Fig. 5) of tempered steel converging at one end toward the nose of a convex protuberance 21 along the center of the top of the block, this protuberance being curvedly recessed concavely, at 22, on the under side of its protruding end, and forming a crimping-pin. These pins project beneath the lip and form therewith intervening grooves 23.

50 On the bed 15 and extending along the wall adjacent the recess 17 is supported a block 24 having right-angle extensions on its ends, through which it is bolted down upon the bed. The upper surface of the block affords a seat for the work and is formed with angular depressions (Fig. 3), into which the pins 21 project for a short distance, and elevations at intervals, as shown, for supporting the work preparatory to operating the tool upon it. A massive block or head 25 is supported on the bed to be guidingly reciprocated relative to the stationary seat-block and jaw 18. It contains in its forward section a rectangular recess 17', in which is seated a jaw 18' terminating at its forward end in a lip 19', in all particulars like the jaw 18 and, like the latter, recessed at opposite sides of its transverse center to contain in the recesses blocks formed with crimping-pins 21' like the crimping-pins 20, and opposing the latter through the seat-depressions. The lips 19' and pins 21' form between them grooves 23', like the grooves 23. A plate 26 covers the reciprocable head-block 25 and is firmly bolted to the bed 15 to hold the jaw 18' in place.

55 A journaling pin 27 is supported adjacent the wall 11 in the opposite bed-frame walls 12 and carries a rocking yoke-link 28 which is connected at its upper end to tail piece 30 by a pivot-pin 29 passing through the elliptical opening in the tail-piece 30 projecting centrally from the rear end of the head 25. A toggle-lever 31 is pivoted at the bifurcated advance-end of its forward section on the pin 29 to embrace the tail-piece 30 and be confined between the prongs of the link 28; and the rear end of the same toggle-section, which is also bifurcated, is

embraced by and connected by a pivot-pin 32 with the bifurcated advance-end of the rear toggle-section, which is connected with a pivot-pin 33 supported in bearings on the rear wall 10 and carries, centrally, a stop 34. On the pivot-pin 32 is journaled at its lower end a link 35, which is embraced by and pivotally connected at its upper end with the bifurcated end of the head of an operating lever 36, fulcrumed in bearings 37 on the bed-frame, and the handle of which may be of any desired length. An adjustable stop-stud 38 is shown to project from the rear face of the link 35 to engage the stop 34 and limit the extent of raising the lever. A wooden stop-block 39 on a ledge 40 at the back of the bed-frame wall 10 and bolted to that wall, limits the extent of lowering the lever, which rests thereon when it has been operated to bring the jaw-lips 19 and 19' into meeting contact.

To operate the tool, with the lever raised, the mutually-overlapping end-portions of a metal strap 41 are introduced into the position represented in Fig. 6, to bear upon the elevated portions of the seat 24 and against the wedge-shaped ends of the stationary pins 20. By thus lowering the handle end of the lever to turn the link 35 forwardly, the toggle 31 is straightened and the link 28 is rocked forwardly to advance the head-block 25. In this advance, the adjacent edge of the work 41 is attacked at two points by the pins 21' and the pressure grips the opposite edges of the work at these and the respectively opposite points between the opposing beveled ends of the crimping-pins, thereby curling the edges into the grooves 23 and 23' outwardly (with relation to the face of the tool). Continued movement of the jaw 18' bends and cups the straps between their edge-portions into the seat-depressions, so that in the final part of the downward movement of the operating lever, which abuts the lips together, the crimping-pins force the outwardly-curved edge-portions of the straps toward each other, as represented in Fig. 7, and the parts coöperate to bulge the crimped strap-sections into the concavely-curved ends of the pins and produce the shape of the joints 42 illustrated in Figs. 8 and 9, thereby firmly locking the straps one within the other. The opening through the tail-

piece 30 being of elliptical shape the pivot-pin 29 has play therein, and the rocking yoke-link 28 through the opening in which the said pin 29 also passes causes the head-block 25 carried by the tail-piece 30 to reciprocate in a straight horizontal line and obviates all binding thereof in its guides. 60

The herein described construction of tool renders it very powerful for its purpose, which it accomplishes without requiring the application of great power to the operating lever and is therefore easy of operation. 65

What we claim as new and desire to secure by Letters Patent is—

1. A tool for jointing metal strap-ends, having a bed-frame, a stationary jaw on the bed of said frame, a head-block reciprocably supported on said bed and having a tail-piece, a jaw carried by the head-block, a seat for the work supported on the bed to extend between the jaws, a link connecting the tail-piece with the frame, a toggle-lever 75 pivotally connected at its forward end with said tail-piece and link and at its opposite end with said frame, a link connected at its lower end with the joint between the toggle-members, and an operating lever fulcrumed 80 in bearings on said frame and connected with the opposite end of the last-named link.

2. A tool for joining metal strap-ends, having a bed-frame, a jaw stationarily supported on the bed of said frame and provided with a lip, a head-block reciprocably supported on said bed and having a tail-piece, a jaw confined on the head-block to reciprocate with it and provided with a lip, crimping-pins projecting opposite each other from the jaw-faces, a seat for the work supported to extend beneath the opposing lips between the jaws, a link connecting said tail-piece with the frame, a toggle-lever pivotally connected at its forward end with said tail-piece and link and at its opposite end with said frame, a link connected at its lower end with the joint between the toggle-members, and an operating lever fulcrumed in bearings on said frame and connected with the opposite end of the last-named link. 90
